ELECTRON DISCHARGE DEVICE

Charles G. Smith, Medford, Mass., assignor, by
mesne assignments, to Raytheon Manufacturing Company, Newton, Mass., a corporation of
Delaware

Application April 24, 1931, Serial No. 532,463
Renewed December 16, 1936

16 Claims. (Cl. 250—93)

This invention relates to electron discharge devices and has special relation to devices in which it is desired to utilize electrons of high speeds. Such a device may be, for example, an X-ray tube.

5 One of the objects of my invention is to obtain high-speed electrons without the use of correspondingly high voltages. The foregoing and other objects of my invention will be best understood from the following description of exemplifications thereof, reference being had to the accompanying drawings, wherein:

10 Fig. 1 is a schematic view of an arrangement whereby high-speed electrons are obtained in accordance with my invention;

15 Fig. 2 is a diagram illustrating certain electrical properties of the arrangement shown in Fig. 1;

Fig. 3 is a view partly in section of an X-ray tube embodying my invention;

20 Fig. 4 is a cross-section taken along line 4—4 of Fig. 3; and

Fig. 5 shows a slightly different form of X-ray tube.

25 In order to obtain high-speed electrons, it has been the usual practice to cause electrons to fall through a high potential. Such high potentials are difficult to obtain and also are difficult to handle. In accordance with my invention I obtain high speeds in electrons without the use of correspondingly high voltages.

30 In order to properly explain the operation of my device, a discussion of the principles and phenomena, which according to my present understanding of the operation of the device are involved, will be given. When an electron moves relative to a magnetic field in a space free of electrical fields, it describes a circle or helix around a line parallel to the magnetic lines of force.

35 The time for an electron to complete a single turn is

$$T = \frac{2\pi m}{He} \quad (\text{Eq. 1})$$

where

40 T = time to complete a single turn.

e = charge of an electron.

m = mass of electron.

H = strength of magnetic field.

$\pi = 3.1416$.

45 50 Since the speed of the electron does not enter into

the above equation, the time T is independent of the radius of the circle or helix along which the electron travels. The speed of the electron is

$$S = \frac{2\pi r}{T} \quad (\text{Eq. 2}) \quad 5$$

where

r = the radius of the circle or helix along which the electron travels.

By the use of Equation 1, this can be expressed as follows:

$$S = r \times H \times \frac{e}{m} \quad (\text{Eq. 3})$$

Since

15

$$\frac{e}{m}$$

is a universal constant, it will be seen that the speed is directly proportional to the field and to the radius of the electron orbit. In accordance with my invention, I obtain electrons of high speed by causing them to travel in an orbit of considerable radius in the presence of an intense magnetic field.

20 Referring to the diagrammatic showing in Fig. 25 1, A, B are two plates maintained a distance apart. Intermediate the plates A and B is a source of electrons C at a distance r_a and r_b from each of said plates A and B, respectively. This may be, for example, a filament heated to a 30 temperature at which it emits electrons. A magnetic field is maintained in a direction perpendicular to the plane of the view shown in Fig. 1. A source of potential E is provided which may be connected across the plates A and B by means of a suitable switching arrangement S. The magnetic field is of such a value that with the potential E disconnected, no electrons reach either plate A or B. In such a case, when the source C emits an electron, that electron will travel in a 40 circular orbit under the influence of the magnetic field, in accordance with Equation 1, and will fall back upon the source C. The circular orbit through which this electron travels may be represented in an exaggerated degree by the circle 45 a having a radius which is proportional to the speed with which the electron is emitted from C.

If at some point in the travel of the electron in the space between A and B, the potential E is impressed across said plates in the proper direc- 50

tion, the electron will be given an acceleration which will cause it to travel in an orbit of larger radius, such as may be indicated by the circle b . Thus the electron will not fall back upon the source C , but will be free to continue its travel in its new orbit b . In order that the electron be subject to an acceleration rather than a deceleration, the voltage E must be in such a direction as to make the plate B positive while the electron is traveling in a direction from A to B . When the electron in its travel reaches that part of its orbit at which it changes its direction of travel between A and B , the voltage which tended to accelerate the electron would tend to decelerate it unless the direction of that voltage also were changed in direction. Thus if it is desired to cause the electron to travel in orbits of constantly increasing diameter, the voltage must change in either magnitude or direction at such a point during each electron orbit that the total acceleration during one orbital rotation of the electron is greater than the total deceleration during said rotation. A voltage which satisfies this requirement is an alternating voltage whose frequency is equal to the orbital frequency of the electron, and which is in phase with the orbital rotation of said electron. The above frequency is equal to

$$\frac{1}{T}$$

which from Equation 1 is

$$f = \frac{H}{2\pi} \frac{e}{m} \quad (\text{Eq. 4})$$

By setting the frequency of the source E at this value and impressing it across the plates A and B , electrons emitted from the source C will be displaced to successive orbits of increasing radii until they fall upon either plate A or B . The speed of the electrons striking the plates A and B can be expressed by Equation 3:

$$S = r \times H \times \frac{e}{m}$$

The factor r will be either r_a or r_b according to which plate the electron falls upon. Since the voltage across the plates A and B does not enter into this equation, it will be seen that I obtain high-speed electrons independently of the voltage of source E .

At each value of speed, an electron has an amount of kinetic energy which can be expressed in terms of voltage as follows:

$$E = \frac{mS^2}{2e} \quad (\text{Eq. 5})$$

where E is the equivalent voltage and S is the speed of the electron. This expression from Equation 3 becomes

$$E = r^2 \times H^2 \times \frac{e}{2m} \quad (\text{Eq. 6})$$

Thus, for example, in a practical case where the distance of C from the nearer plate is but $1\frac{1}{2}$ cm. and the field H is but 500 gauss, each electron striking the nearer plate will have an effective voltage of approximately 50,000 volts. The requisite frequency and consequently the wave length of the source C can be calculated from Equation 4. In the particular case given above, the wave length of the source would be about 24 cm. Such a source is one of very high frequency but oscillators, which generate such short wave lengths and even shorter ones, have been devised.

Although I have described the voltage E as being of exactly the same frequency as the orbital

frequency of the electron and in phase with said orbital frequency, yet both the frequency and the phase may vary from these values within certain limits. When the frequency of the voltage E is varied with respect to the orbital frequency as calculated from Equation 4, a number of electrons still reach the plates A and B . The number of these electrons decreases as the difference between the two frequencies increases until at a certain point none of the electrons reach either A or B . According to my present understanding of the phenomena involved, this result may be explained as follows:

In Fig. 2, curve D represents the variation with respect to time of the component of velocity in a direction perpendicular to plates A and B of an electron traveling in an orbit such as d . The direction A to B is taken as positive. The curve F represents the voltage of source E , the positive values being taken as those when B is positive. When A or B is positive, an electron will be attracted towards that plate. Thus when both D and F are both negative or both positive, the electron will be accelerated. When D and F are of opposite signs, the electron will be decelerated. Since the total change in speed of the electron depends on the value of voltage and the time during which it acts, the total change in speed of an electron during one orbit can be measured by the difference of the integration of the voltage during the time both F and D are of the same sign and the integration of the voltages during the time F and D are of opposite signs.

In Fig. 2, F is assumed as lagging D by 90° . During each cycle of the voltage F , D and F are both of the same sign from J to T and from U to V , and of opposite signs from T to U and from V to W . The difference of the integrations of these two sets of values is zero. Thus if an electron lags or leads the voltage by 90° , the total change in acceleration during one orbital cycle will be zero, and such an electron on being emitted from the source C will fall back on said source. It can be shown that all electrons which lead or lag the voltage by more than 90° , will be given an effective deceleration through one orbital cycle, and when emitted from the source C will be forced back onto said source. All electrons differing in phase angle from the voltage by less than 90° , will be given an effective acceleration during each orbital cycle, and will be forced into orbits of increasingly large radius until they finally strike either plate A or B . Since C emits electrons continuously, the space immediately around C will contain electrons having orbital cycles having all possible phase angles with respect to the voltage between A and B . Assuming that E has the frequency given by Equation 4, then all electrons in a sector 180° wide, the center of said sector rotating in phase with the voltage E , will be accelerated and will finally reach either plate A or B . This is strictly true only if C is a point source. Since C , however, will have an appreciable cross-section, electrons at the outer edges of the 180° sector will not be given sufficient acceleration and consequent displacement to clear the source C during one orbital cycle. Thus the effective size of the sector is less than 180° . This effect increases with increases in the diameter of the source C , and therefore it is advisable to keep the cross-sectional area of C as small as can be done practically.

Due to the fact that the phase angle between the orbital rotation of an electron and the voltage between the plates may vary through practically

180° and yet produce the desired result, the frequency of the voltage need not be exactly equal to the orbital frequency of the electron as obtained in Equation 4. If a voltage of some other frequency differing slightly from said orbital frequency is used, an electron in the active sector will advance or drop back in the sector by a definite angle during each orbital cycle, depending on the difference in the orbital frequency and the frequency of the source E. Thus an electron can travel through a number of cycles until it has gained or lost enough angular distance with respect to the active sector to enter the inactive sector wherein it will be deflected back to the source C. The maximum number of such cycles in any case depends on the size of the angle gained or lost during each cycle, and the width of the active sector. If such an electron receives sufficient acceleration during such cycles, it will reach one of the plates. Thus the frequency of the voltage E can vary with respect to the orbital frequency of the electrons with entirely cutting off the supply of electrons to the plates. However, the total number of electrons reaching the plates decreases as the difference in frequency increases until at a certain magnitude of difference, none of the electrons will reach the plate. The number of electrons reaching the plate is at a maximum when the orbital frequency and the voltage frequency are equal.

While the results reached as described above are independent of the magnitude of the voltage between A and B, there are certain practical considerations which require that this voltage be not of too low a value. The total increase in speed which an electron undergoes during one orbital cycle depends directly on the value of the voltage between A and B. If this voltage is small, the electron will be forced to travel through a large number of orbital cycles before it finally reaches one of the plates. Since the permissible difference in frequency between the voltage and the orbital frequency decreases with an increase in the number of orbital cycles through which said electron passes, if the value of voltage is low, the difference of such frequencies must be low. In practice, the frequency of the source E is often slightly different from the orbital frequency, and therefore it is desirable that the magnitude of the voltage be kept sufficiently high to take care of this factor.

Another factor which limits the number of orbital cycles permissible is that due to the increase in the apparent mass of an electron at very high speeds in accordance with the accepted theory of relativity. Since in accordance with Equation 4 the orbital frequency varies inversely with the mass of the electron, if the orbital frequency and the frequency of the voltage F at the initial low speeds of the electrons are equal, this equality is no longer true at the higher speeds of the electron. The effect of the difference between these two frequencies becomes appreciable at high electron speeds, and places a limitation on the value of the voltage applied between the plates, as explained above. I have, however, devised a simple means for compensating for the relativity effect which will be explained in connection with one of the modifications described below.

In addition to the above factors, an increase in the number of orbital cycles for any given current between the source C and the plates A and B, increases the total number of electrons existing at any one time between the source C

and the plates A and B. These electrons create a space charge which tends to reduce the number of electrons reaching the plates. It is desirable to keep the space charge as low as possible. In the practical example cited above, a voltage of about 1000 volts could be used satisfactorily between the plates A and B.

A particularly useful application of high-speed electrons as obtained above is in X-ray tubes. X-rays are produced by causing electrons to collide at high speed with a target of some material, such as, for example, tungsten. Upon the electrons colliding with the target, X-rays are emitted. With an increase in the speed at which the electrons collide with the target, the wave length of the X-rays becomes shorter and the penetrating power of such rays becomes greater. Such an increase in the penetrating power of the X-rays is termed an increase in hardness of these rays. Voltages of between 20,000 to 200,000 volts between the electron source and the target have been used to obtain X-rays. My invention, however, affords a means for obtaining X-rays of extreme hardness without the use of such high voltages.

Figs. 3 and 4 show an X-ray tube embodying my invention. Two plates 1 and 2 and a filament 3 are supported on the upper end of a reentrant stem 4 within an evacuated envelope 5. The top of the stem is closed by a depending section 7 having a tube 8 through which the envelope 5 is evacuated. The junction between the section 7 and the upper part of the stem forms a ring portion in which are sealed the plate-supporting standards 9, 10, 11 and 12, and the filament-supporting standards 13 and 14. The plate 1 is supported on the standards 9 and 10. A wedge-shaped member or target 20 is attached to the face of the plate 1 by some such means as welding or riveting. This target is adapted to serve as a source of X-rays, and is made preferably of tungsten. The plate 2 is supported on the standards 11 and 12. Both plates 1 and 2 are formed of conducting material, such as nickel or molybdenum. The standards 9 and 11, respectively, are connected to wires 15 and 16 which serve as external electrical connections for the plates 1 and 2, respectively. The filament 3 is stretched between the standards 13 and 14, preferably along the axis of the tube midway between the plates 1 and 2. This filament is adapted to emit electrons when heated, and is preferably made of tungsten. The standards 13 and 14 are connected to wires 18 and 19, respectively, which serve as external electrical connections to opposite ends of the filament. A coil 21 surrounds the envelope 5, and is adapted to create a magnetic field in the space between the two plates 1 and 2. My X-ray tube may be provided with a plate 22 made of lead and having an opening or window 23 through which X-rays emitted from the target member 20 may pass. In this manner the X-rays may be confined to a limited path.

A suitable source of heating current may be connected to the filament leads 18 and 19. Such a source may be, for example, a transformer 24 fed from an alternating current line. A suitable source of high frequency voltage is connected between the two plate leads 15 and 16. Such a high frequency source is indicated at 25, and may be connected to the two plates by means of the inductively coupled coils 26 and 27. The coil 26 is connected to the source 25 and the coil 27 to the conductors 15 and 16. The frequency of the source 25 may be regulated by a control member, 75

indicated at 25'. An ammeter 33 is connected between a point intermediate the ends of the coil 27 and the filament. The connection to the filament may be made through the conductor 19. 5 The ammeter 33 will read the total amount of current flowing between the plates and the filament. It is also desirable to ground the point at which the connection from the conductor 19 to the intermediate point on the coil 27 is made. 10 This is done in Fig. 3 by the conductor 30 connected to a point intermediate the ends of the coil 27.

The coil 21 may be energized from some suitable source of direct current, such as a battery 31. In series with said battery is a regulating member 32 which may be an adjustable resistance. An ammeter 32' in series with the circuit can be used to indicate the amount of current flowing through coil 21.

20 The interior of the container 5 is thoroughly evacuated in order that any current passing between the filament 3 and the plates 1 and 2 is maintained primarily by the electron emission from the filament 3. However, a very small 25 amount of gas within the envelope does no harm and may be actually beneficial. Such a small amount of gas will be ionized by some of the electrons and produce positive ions which will reduce the space charge within the tube. However, the 30 quantity of gas within the envelope must be kept at a sufficiently low value so that the passage of current resulting from the ionization of such gas forms a negligible part of the total space current passing through the tube.

35 When the various parts are connected, as shown in Fig. 3, the current of transformer 24 will heat the filament 3 to a temperature at which it emits large numbers of electrons. These electrons under the joint influence of the field created by the coil 21 and the electrostatic field existing between the plates 1 and 2, due to the high frequency source 25 will travel in orbital paths around the filament 3 in accordance with the explanation as given for Fig. 1, and will finally strike the target 40 20 at high speeds. Since the target 20 is placed closer to the filament 3 than are either the plates 1 or 2, practically all of the electrons which reach the outer orbits will fall upon the target 20, and comparatively few will fall upon either the plate 45 1 or 2. Thus the target 20 becomes a source of 50 X-rays. This source of X-rays will be practically a linear one. However, when viewed from that end of the tube from which the X-rays are adapted to be used, this linear source appears as a 55 point source.

55 In the device as described above, both the quantity and hardness of the X-rays emitted from the tube may be controlled in a particularly simple and efficient manner. An increase in the 60 hardness of the X-rays may be accomplished by increasing the intensity of the magnetic field by means of the regulating resistance 32 and increasing the frequency by means of the regulating member 25' in corresponding degree. The hardness 65 of the X-rays is decreased by decreasing both the intensity of the magnetic field and the frequency. Since the hardness of the X-rays in each case depends on the value of the field, and since the field varies in accordance with the current through coil 21, the amount of this current 70 is a measure of the hardness of the X-rays. Thus meter 32' which indicates the amount of the current can be used to indicate the hardness of the X-rays. The quantity of X-rays emitted 75 may be decreased by varying the frequency of

the source 25 away from the resonant orbital frequency of the electrons in the tube. Similarly by the quantity of X-rays may be decreased by allowing the frequency of the source 25 to remain constant but varying the intensity of the magnetic field so that the orbital frequency of the electrons is no longer the same as that of the source 25. Since the quantity or intensity of the X-rays depends upon the number of electrons striking the target 20, it will be seen that the amount of space current passing through the tube is a measure of the intensity of the X-rays emitted by the tube. Thus the ammeter 33 which reads the space current flowing between the filament and the plates can be used to indicate the intensity of the X-rays.

As stated above, the relativity factor or increase in the apparent mass of an electron at high speeds produces an appreciable effect on the orbital period of an electron. I have found that by causing an electron to pass into magnetic fields of increasing value, as the speed of the electron increases the orbital period of the electron can be kept practically constant. The explanation of this can be had by referring to Equation 3. The orbital period is directly proportional to the mass of the electron, and inversely proportional to the intensity of the magnetic field. Since the mass of the electron depends on its speed, it will be seen that by increasing the field as the speed of the electron increases, the orbital period of the electron can be kept constant.

In Fig. 5 I have shown, by way of example, an X-ray tube in which I cause the electrons to travel in a magnetic field of increasing intensity as the speed of the electron increases, thereby compensating for the relativity factor. In the tube, as shown in Fig. 5, the ultimate speeds which the electrons obtain can be extended in a practical case to considerably higher values than 40 in a tube as shown in Fig. 3. Fig. 5 discloses two elongated plates 51 and 52 supported within an elongated evacuated tube 53. The two plates 51 and 52 are supported within the tube 53 above a press 54 at the upper end of a reentrant stem 55 45 by two supporting standards 56 and 57, respectively. The plate 51 carries at its upper end a wedge-shaped target 58 similar to the target 20 of Fig. 3. A thermionic filament 59 is supported in the lower end of the tube 53 by means of lead-in 50 wires sealed into the press 54. The parts are so arranged that the lower ends of the plates 51 and 52 are supported at an appreciable distance above the filament 59. A coil 60 surrounds the tube 53 for the purpose of creating a magnetic 55 field in the space between the plates 51 and 52. This coil is made in such a manner that the field which it creates is greatest in intensity at the top of the tube, and decreases in intensity towards the bottom thereof. This variation in field intensity may be accomplished, for example, by forming the coil 60 with a greater number of turns in the top portion than in the bottom portion. This produces the trapezoidal cross-section of each half of the coil, as shown in Fig. 5. 60 The tube 53 may also be provided with a shielding plate 61 which is similar to plate 22. Conductors 62 and 63 are connected to opposite ends of the filament 59. A heating transformer 64 may be used to furnish heating current for the filament 65 70 59. Two conductors 65 and 66 are connected to the standards 56 and 57 of the plates 51 and 52, respectively. A source of high frequency current 67 is connected between the two conductors 65 and 66 by means of the coupling coils 68 and 69. 75

This source 67 may also be regulated by means of a regulating member 70. In order to cause the electrons which are emitted from the filament 59 to travel up towards the target 58, I introduce a 5 battery 71 connected between one of the filament leads 62 and a point intermediate the ends of the coil 69.

When the filament is heated to the proper temperature, it emits electrons. These electrons 10 travel in orbital paths under the joint influence of the field between the plates 51 and 52 and the magnetic fields due to the coil 60, in accordance with the explanation given in the early part of this specification. In addition, the electrons 15 are given a velocity along the tube towards the upper end thereof. This is due to the potential created between the filament 59 and the two plates 51 and 52 by the battery 71. This battery is connected in such a manner that electrons 20 emitted from the filament 59 are attracted upwardly towards the two plates 51 and 52. As each electron passes up through the tube, its orbital radius steadily increases due to the acceleration which it receives from the electrostatic 25 field between the two plates 51 and 52. Since the intensity of the magnetic field also increases along the tube, it will be seen that as the radius of the orbital path and consequently the speed of the electron increase, the electron 30 passes into a magnetic field of greater intensity. By properly designing the coil 60, the orbital frequency of the electrons can be kept constant. An increase of about one or two per cent. in the intensity of the field from the bottom to the top 35 thereof is usually sufficient to compensate for the relativity factor in a practical tube. Since with such a tube, as described above, the electrons may be given extremely high speeds without introducing any disturbing effects due to the relativity factor, such a tube may be used to obtain electrons of very high speed and consequently 40 X-rays of extreme hardness.

This particular invention is not limited to the particular details of construction, materials or 45 processes described above as many equivalents will suggest themselves to those skilled in the art. It is accordingly desired that the appended claims be given a broad interpretation commensurate with the scope of the invention within the art.

50 What is claimed is:

1. In an electron discharge device, a sealed envelope containing a source of electrons, the gas pressure in said envelope being sufficiently low so that the discharge which occurs is a substantially 55 pure electron discharge, means for creating a magnetic field into which electrons coming from said source pass, whereby the electrons are given a definite orbital period, and means for subjecting said electrons to a varying electrostatic field whose period is substantially equal to the orbital period of the electrons.

2. An X-ray tube comprising an evacuated vessel, two electrodes within said vessel, an elongated thermionic cathode intermediate said electrodes, one of said electrodes carrying a target, means for creating a magnetic field between said electrodes in such a direction as to prevent electrons from said source from reaching said electrodes, and means for impressing a varying electrostatic field between said electrodes of such a 65 periodicity as to cause electrons from said source to strike said target.

3. An electron discharge device comprising a 70 sealed envelope containing a source of electrons,

the gas pressure in said envelope being sufficiently low so that the discharge which occurs is a substantially pure electron discharge, means for creating a magnetic field into which electrons coming from said source pass, whereby said electrons are given a definite orbital period, means for subjecting said electrons to a varying electrostatic field whose periodicity is substantially equal to the orbital periodicity of the electrons, said first-named means being arranged to cause at least a portion of the said magnetic field to be of increased intensity, and means for giving said electrons a drift velocity into the region of greater field intensity. 5

4. An electron discharge device comprising an evacuated vessel containing two spaced electrodes, a thermionic cathode outside of the space between said electrodes but located on a line intermediate said electrodes, means for creating a magnetic field within said vessel whereby said 10 electrons are given a definite orbital period, said magnetic field increasing in intensity from the region around said cathode to the region adjacent the opposite ends of said electrodes, means for establishing a potential between said electrodes and said cathode, whereby electrons coming from said cathode are given a drift velocity towards said electrodes, and means for impressing a varying electrostatic force across said electrodes, the periodicity of which is substantially 15 equal to the orbital periodicity of said electrons. 20

5. A high-speed electron discharge device including a sealed envelope containing a source of electrons, the gas pressure in said envelope being sufficiently low so that the discharge which occurs is a substantially pure electron discharge, means for creating a magnetic field into which said electrons pass, whereby they are given a definite orbital period, means for subjecting said electrons to a varying electrostatic field, the periodicity of which is substantially equal to the orbital periodicity of said electrons, an element spaced from said source against which said electrons are caused to impinge, means for varying the intensity of said magnetic field, and independent means for varying the periodicity of said electrostatic field. 35

6. A high-speed electron discharge device including a sealed envelope containing a source of electrons, the gas pressure in said envelope being sufficiently low so that the discharge which occurs is a substantially pure electron discharge, means for creating a magnetic field into which said electrons pass, whereby they are given a definite orbital period, means for subjecting said electrons to a varying electrostatic field, the periodicity of which is substantially equal to the orbital periodicity of said electrons, an element spaced from said source against which said electrons are caused to impinge, and means for varying the intensity of said magnetic field. 50

7. A high-speed electron discharge device including a sealed envelope containing a source of electrons, the gas pressure in said envelope being sufficiently low so that the discharge which occurs is a substantially pure electron discharge, means for creating a magnetic field into which said electrons pass, whereby they are given a definite orbital period, means for subjecting said electrons to a varying electrostatic field, the periodicity of which is substantially equal to the orbital periodicity of said electrons, an element spaced from said source against which said electrons are caused to impinge, and means for varying the periodicity of said electrostatic field. 55

8. The method of obtaining a high-speed electron which comprises subjecting said electron to a strong magnetic field, whereby it is given a definite orbital period and giving said electron 5 definite electrostatic accelerating impulses during each orbital rotation, whereby it is caused to travel in orbital paths of increasing radii at successively higher speeds.

9. The method of controlling a flow of electrons which comprises subjecting said electrons to a magnetic field, whereby they are given a definite orbital period, and subjecting said electrons to a periodically varying electrostatic field, the period of said electrostatic field being substantially 10 equal to the orbital period of said electrons.

10. The method of controlling a flow of electrons between a cathode and an anode which comprises subjecting said electrons to a magnetic field, whereby they are given a definite orbital period, and subjecting said electrons to a periodically varying electrostatic field, the period of 20 said electrostatic field being substantially equal to the orbital period of said electrons, and varying the number of electrons reaching said anode by 25 varying the periodicity of said electrostatic field, the number of electrons reaching said anode decreasing as the period of said electrostatic field differs more widely from said substantial equality.

11. The method of controlling a flow of electrons between a cathode and an anode which comprises subjecting said electrons to a magnetic field whereby they are given a definite orbital period, and subjecting said electrons to a periodically varying electrostatic field, the period of 30 said electrostatic field being substantially equal to the orbital period of said electrons, and varying the velocity of electrons reaching said anode by varying the intensity of said magnetic field.

12. The method of controlling X-rays caused 40 by electrons coming from a cathode impinging upon a target which comprises subjecting said electrons to a magnetic field whereby they are given a definite orbital period, and subjecting said electrons to a periodically varying electrostatic field, the period of 45 said electrostatic field being substantially equal to the orbital period of the electrons.

said electrons, and varying the quantity of X-rays generated by varying the periodicity of said electrostatic field, the quantity of X-rays generated decreasing as the period of said electrostatic field differs more widely from said substantial equality. 5

13. The method of controlling X-rays caused by electrons coming from a cathode impinging upon a target which comprises subjecting said electrons to a magnetic field whereby they are given a definite orbital period, and subjecting said 10 electrons to a periodically varying electrostatic field, the period of said electrostatic field being substantially equal to the orbital period of said electrons, and varying the intensity of the X-rays generated by varying the intensity of said magnetic field. 15

14. The method of obtaining a high-speed electron which comprises subjecting said electron to a magnetic field, whereby it is given a definite orbital period, and giving said electron 20 electrostatic accelerating impulses during its orbital rotations, whereby it is caused to travel in orbital paths of increasing radii at successively higher speeds.

15. In a space discharge device, a sealed envelope containing a source of negatively-charged particles, the gas pressure in said envelope being sufficiently low so that the discharge which occurs is a substantially non-ionizing discharge, means for creating the magnetic field into which negatively-charged particles coming from said source pass, whereby the negatively-charged particles are given a definite orbital period, and means for subjecting said negatively-charged particles to a varying electrostatic field whose period is substantially equal to the orbital period of the electrons. 30 35

16. The method of obtaining a high-speed negatively-charged particle which comprises subjecting said negatively-charged particle to a magnetic field, whereby it is given a definite orbital period, and giving said negatively-charged particle 40 electrostatic accelerating impulses during its orbital rotations, whereby it is caused to travel in orbital paths of increasing radii at successively higher speeds. 45
